WAVE MOTOR

Harm D. Snell, Port Arthur, Tex.

Application October 29, 1932. Serial No. 640,297

5 Claims. (Cl. 253—10)

The present invention relates to a wave motor and has for its object to provide means whereby a series of floats may be progressively raised by a wave and the upward motion thereof transferred to rotary motion of a shaft.

Another very important object of the invention resides in the provision of a mechanism of this nature which is comparatively simple in its construction, inexpensive to manufacture and assemble, strong and durable, thoroughly efficient and reliable in use and operation and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

20 In the drawings:

Figure 1 is a top plan view of a wave motor embodying the features of my invention.

Figure 2 is a vertical transverse section taken substantially on the line 2—2 of Figure 1.

25 Figure 3 is an enlarged detail section taken substantially on the line 3—3 of Figure 1.

Figure 4 is a side elevation of the mechanism.

Figure 5 is an end elevation thereof, and

30 Figure 6 is a detail section through the upper portion of one of the uprights.

Referring to the drawings in detail it will be seen that the numeral 5 denotes an oblong concrete base having a frame rising therefrom. The frame is made up of a plurality of uprights disposed in spaced relation. Each upright is of a substantially inverted V-shaped formation and includes a pair of angle iron sides 6 the upper ends of which are secured together so that the sides diverge downwardly toward each other terminating at their lower ends in vertical extensions 7 which are anchored on the base 5. These sides are preferably constructed of angle iron. A brace 8 extends between the upper ends of the extensions 7. A bearing block 9 is fixed on the upper end of each upright and has a cap 10 associated therewith being held in place by means of bolts 11 or the like. A shaft 12 is journaled in the bearing. Extending from both sides of the block 9 are arms 14. Each arm 14 terminates in a sleeve 15. Rods 16 and 17 extend through these sleeves. Braces 18 have openings through which the rods extend and are locked against the sleeves 15 by nuts 20. The braces 18 are secured to the adjacent sides 6 of the uprights. Levers

50 21 are rockable intermediate their ends on the

rods 17 between collars 22. Pairs of cranks 23 are rockable on the shaft 12 and are connected by pins 24 to links 25 and the links 25 are connected by pins 26 to the inner ends of the levers 21. Each pair of cranks 23 has rockable therebetween on a pin 27, a pawl 28 with a spring 29 associated therewith for pressing the same into engagement with the ratchet 30 keyed on the shaft 12 between said pair of cranks.

Link rods 31 are pivoted to the outer ends of the levers and are pivotally engaged with floats 32 which are movable between upright guides 34 mounted on the base 5. From the description as it has thus far progressed it will be readily seen that as a wave moves from one float to the other it will cause the float to rise thereby rocking the corresponding lever and rocking the corresponding crank so as to move the pawl over the ratchet wheel and when the wave passes by or recedes the weight of the float will rock the lever in the opposite direction so that the upward swinging movement of the cranks will cause the pawl to engage a tooth in the ratchet wheel and thereby rock the shaft. In this way it will be seen that a continuous rotary motion may be imparted to the shaft 12.

The power generated by the mechanism may be used in various ways. In the present embodiment of the invention I have illustrated a platform 30' extending from one of the end uprights 31 and braced as at 31. On this platform is a transmission mechanism 32 operatively connected with a generator 33. The transmission mechanism includes a shaft 34 on which is a gear 35 meshing with the gear 36 on the adjacent end of the shaft 12.

The present embodiment of the invention has been described in considerable detail merely for the purposes of exemplification since in actual practice it attains the features of advantage 95 enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A wave motor of the class described including a base, uprights rising from the base, a shaft journaled on the uprights, arms extending from the uprights, a rod supported in the arms to one side of the uprights, levers rockable interme-

diate their ends on the rod between the uprights, means operatively connecting the levers with the shaft so that the oscillatory movement of the levers may be transformed into rotary motion of the shaft, a plurality of groups of guides rising from the base, a float movable between the guides, and links connecting the floats with the levers.

2. A wave motor of the class described including a base, uprights rising from the base, a shaft journalled on the uprights, arms extending from the uprights, a rod supported in the arms to one side of the uprights, levers rockable intermediate their ends on the rod between the uprights, means operatively connecting the levers with the shaft so that the oscillatory movement of the levers may be transformed into rotary motion of the shaft, a plurality of groups of guides rising from the base, a float movable between the guides, and links connecting the floats with the levers, said first mentioned means comprising ratchets on the shaft, cranks rockable on the shaft adjacent the ratchet, pawls carried by the cranks, springs engaging the pawls to urge them into engagement with the ratchet, and links connecting the other ends of the levers with the cranks.

3. A wave motor of the class described including a base, uprights rising from the base, a shaft journalled on the uprights, arms extending from the uprights, a rod supported in the arms to one side of the uprights, levers rockable intermediate their ends on the rod between the uprights, means operatively connecting the levers with the shaft so that the oscillatory movement of the levers may be transformed into rotary motion of the shaft, a plurality of groups of guides rising from the base, a float movable between the guides, and links connecting the floats with the levers, each upright comprising a substantially V-shaped member composed of a pair of angle iron sides.

4. In a wave motor of the class described, a frame comprising a plurality of uprights, each

upright being of a substantially inverted V-shaped formation to include a pair of sides connected together at their upper ends and diverging downwardly from each other and merging into vertical lower portions, braces between the upper ends of the vertical portions, bearings on the upper ends of the uprights, and a shaft journalled in said bearings, arms extending from the bearings to the sides of the uprights and terminating in sleeves, a rod extending through said sleeve, a plurality of levers rockable intermediate their ends on the rod between the uprights, float actuated means for oscillating the levers, and means between the levers and the shaft for transforming the oscillatory motion of the levers into rotary motion of the shaft.

5. In a wave motor of the class described, a frame comprising a plurality of uprights, each upright being of a substantially inverted V-shaped formation to include a pair of sides connected together at their upper ends and diverging downwardly from each other and merging into vertical lower portions, braces between the upper ends of the vertical portions, bearings on the upper ends of the uprights, and a shaft journalled in said bearings, arms extending from the bearings to the sides of the uprights and terminating in sleeves, a rod extending through said sleeve, a plurality of levers rockable intermediate their ends on the rod between the uprights, float actuated means for oscillating the levers, a plurality of ratchet wheels on the shaft between the uprights, a pair of cranks rockable on the shaft associated with each ratchet wheel to provide one crank on each side thereof, a pin between the outer ends of the cranks, a link engageable with said pin and with the corresponding lever, a pawl rockably mounted between each pair of cranks, spring means associated with the pawls to normally urge them into engagement with the ratchet.
